(57) **CLAIM**

The ornamental design for a microphone set as shown and described.

DESCRIPTION

FIG. 1 is a front, top perspective view of a first piece of the microphone set showing my new design;

FIG. 2 is a rear, bottom perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a front, top perspective view of an adapter of the microphone set showing my new design;

FIG. 10 is a rear, bottom perspective view thereof;

FIG. 11 is a front view of FIG. 9;

FIG. 12 is a rear view of FIG. 9;

FIG. 13 is a left side view of FIG. 9;

FIG. 14 is a right side view of FIG. 9;

FIG. 15 is a top plan view of FIG. 9;

FIG. 16 is a bottom plan view of FIG. 9;

FIG. 17 is a front, top perspective view of an earphone of the microphone;

FIG. 18 is a rear, bottom perspective view thereof;

FIG. 19 is a front view of FIG. 17;

FIG. 20 is a rear view of FIG. 17;

FIG. 21 is a left side view of FIG. 17;

FIG. 22 is a right side view of FIG. 17;

FIG. 23 is a top plan view of FIG. 17;

FIG. 24 is a bottom plan view of FIG. 17; and,

(Continued)

FIG. 25 is a perspective view of the microphone set shown in an assembled configuration.

The broken lines in the drawings depict portions of the microphone set that form no part of the claimed design.
